UNITED STATES PATENT OFFICE.

LEBBEUS B. MILLER, OF ELIZABETH, NEW JERSEY, ASSIGNOR TO THE
SINGER MANUFACTURING COMPANY OF NEW JERSEY.

MACHINE FOR SWAGING NEEDLE-BLANKS.

SPECIFICATION forming part of Letters Patent No. 364,274, dated June 7, 1887.

Application filed February 12, 1887. Serial No. 227,398. (No model.)

To all whom it may concern:

Be it known that I, LEBBEUS B. MILLER, a citizen of the United States, residing at Elizabeth, in the county of Union and State of New Jersey, have invented certain new and useful Improvements in Machines for Swaging Needle-Blanks, of which the following is a specification, reference being had therein to the accompanying drawings.

10 My invention relates to a machine such as is shown by the patent to W. H. Dayton, No. 268,874, dated December 12, 1882, for swaging needle-blanks and other similar articles. In the machine shown by the said patent the dies 15 are carried by a rotary holder and are forced toward each other by a circularly-arranged series of rollers, against which the outer ends of the dies, or the contact-blocks forming continuations of the said dies, impinge as the die- 20 holder revolves.

In the machines of the class referred to adjustment of the dies, either to compensate for the loss of metal by wear or resurfacing, or for swaging different sizes of needles, has heretofore been effected by inserting steel plates or 25 "filling-pieces" of varying thickness between the dies and the contact-blocks; but this means of adjustment has been found objectionable and unsatisfactory, and the object of my invention is to overcome the inconvenience incidental thereto. This object I accomplish by providing wedges, which are interposed between the dies and the contact-blocks, and which may be adjusted as may be desired to adjust the 30 dies.

35 In the accompanying drawings, Figure 1 is a sectional view of a rotary die-holder and the parts carried thereby embodying my invention. Fig. 2 is an end or face view of the same. Fig. 3 is a view similar to Fig. 2, showing the die-holder and the parts rotating therewith, and also the rollers for forcing the dies toward each other, and the stationary cylinder or shell within which the said rollers are housed; and 40 Figs. 4, 5, 6, and 7 are enlarged detail views.

A denotes the rotary die-holder, which is grooved or recessed for the reception of the dies B and the contact-blocks C, and between the said blocks and dies are interposed the 45 adjusting-wedges D, the outer ends of which are formed with right-angular arms d, pro-

vided with slots or openings d' for the free passage of the screws F, the latter having solid collars f impinging against the inner sides of the said arms. The said screws are also provided with lock-nuts G, and between the said nuts and the outer faces of the said wedges I prefer to interpose the washers b. The inner ends of the contact-blocks C are beveled to correspond to the bevel of the wedges, and 55 as it is desirable that the latter should have a bearing against the entire surfaces of the ends of the said blocks and of the dies, the die-holder is provided with recesses a, into which the ends of said wedges may project as they 60 are adjusted inward. The rollers E, by which the dies are forced inward, are arranged in a circle inside of the stationary shell or cylinder H, in which they are retained by the annular bearing-plate I.

70 From the foregoing it will be apparent that adjustment of the dies may conveniently be effected by turning the screws F in or out, the accidental displacement of the said wedges being prevented by the lock-nuts G, which are 75 tightened after adjustment of the screws. The slots d', formed in the arms d of the wedges for the passage of the screws F, permit the necessary side movement of the said wedges as they are adjusted in and out.

80 To provide for accurate adjustment of the wedges, and to secure exactly the same adjustment of both wedges without difficulty, I prefer to key the washers b to the screws F, so that they will turn with the latter, said washers for this purpose being furnished with index-figures and the outer faces of the wedges with gage-marks, (see Fig. 6,) so that the extent of the rotation of the said screws will be indicated by the washers. The wedges are 85 also preferably provided at their outer ends with graduated scales c; and by means of these scales and the index-washers adjustments equaling in exactness those determined by micrometer gages may conveniently be effected. 90 This feature of my invention will be readily understood by reference to Figs. 4, 5, 6, and 7, the last-named figure showing a notch, b', in one of the washers for loosely keying it to its screw, so that it will turn with the latter, 95 although the screw will be free to move lengthwise through the washer.

I claim—

1. The combination, with the die-holder and the dies and contact-blocks carried thereby, of the adjustable wedges interposed between 5 the said dies and blocks, substantially as set forth.
2. The combination, with the die-holder and the dies and contact-blocks carried thereby, of the wedges interposed between the said dies 10 and blocks, and the screws for adjusting said wedges, substantially as set forth.
3. The combination, with the die-holder and the dies and contact-blocks carried thereby, of the wedges D, interposed between said dies and 15 blocks and provided with slotted arms d, the screws F, having the collars f, and the lock-nuts G, substantially as set forth.
4. The combination, with the die-holder A, having the recesses a, of the dies and contact- 20 blocks carried by said holder, and the adjustable wedges interposed between the entire adjacent surfaces of the said dies and blocks and adapted to extend into said recesses when adjusted inward, substantially as set forth.
- 25 5. The combination, with the die-holder, the dies, the contact-blocks, the wedges, and the

screws F, having collars f, of the lock-nuts, and the washers interposed between said nuts and the outer ends of the arms of the said wedges, substantially as set forth. 30

6. The combination, with the die-holder, the dies, and the contact-blocks, of the wedges interposed between the said blocks and dies, the screws for adjusting said wedges, the washers keyed to said screws and provided with index- 35 figures, and the lock-nuts for securing said screws after adjustment, substantially as set forth.

7. The combination, with the die-holder, the dies, and the contact-blocks, of the wedges interposed between the said dies and blocks and provided at their outer ends with graduated 40 scales, the screws for adjusting said wedges, the index-washers, and the lock-nuts, substantially as set forth.

In testimony whereof I affix my signature in presence of two witnesses.

LEBBEUS B. MILLER.
